PIPE WRENCH

Filed May 1, 1925

UNITED STATES PATENT OFFICE.

DONALD M. STAINBROOK, OF ORLAND, OHIO.

PIPE WRENCH.

Application filed May 1, 1925. Serial No. 27,162.

To all whom it may concern:

Be it known that I, DONALD M. STAINBROOK, a citizen of the United States, residing at Orland, in the county of Vinton and State of Ohio, have invented certain new and useful Improvements in Pipe Wrenches, of which the following is a specification.

This invention relates to wrenches for engaging with pipes, rods, shafts and other similar objects; and it consists in the novel construction and combination of the parts hereinafter fully described and claimed.

In the drawings, Figure 1 is a side view of a wrench constructed according to this invention. Fig. 2 is a plan view of the same. Fig. 3 is a detail plan view of a portion of one of the jaw sections showing the facing. Fig. 4 is a cross-section, taken on the line 4-4 in Fig. 3.

The wrench is provided with a jaw formed of two curved jaw sections 6 and 7 connected together pivotally by a hinge 8. These jaw sections are formed of bands of sheet metal the faces of which are provided with a facing of heavy textile material formed of two superposed layers 9 and 10. The rear part 9 may be formed of felt, and is a continuous and unbroken strip. The front part 10 is heavy woven material, such as canvas, and it has friction plugs 12 inserted in holes in it, the bottoms of the plugs being arranged to bear on the layer of felt 9. These plugs are formed of cork or soft wood. The two layers can be secured together in any convenient way, as by stitches, and the strip of facing is placed loosely over the jaw sections, but it may be secured to them if desired. These bands of sheet metal with their facing are arranged broadside of the axis of the jaw, that is to say their broad curved faces are arranged circumferentially around the axis of the jaw so as to encircle and bear on the periphery of a pipe and bend a little and adapt themselves to its surface.

One jaw section has an eye 14, and a bail-shaped link 15 is pivoted to this eye. The operating lever 16 is pivoted to the link 15 by a pin 17, and has a curved jaw 18 on one end portion provided with teeth. The other jaw section 7 has a curved block 19 secured to it, and also provided with teeth. All the teeth are ratchet-shaped, and the block 19 is thickest at its middle part. The block 19 is arranged diametrically opposite the pivot hinge of the two jaw sections.

The jaw sections and their facing adapt themselves automatically to cylindrical objects of different diameter, such as pipes, and the facing provided with cork plugs enables the jaw sections to engage the object without slipping. A pipe 20 is indicated in dotted lines, and when the parts are in the positions shown in Fig. 1, and the lever is moved in the direction of the arrow, the pipe is gripped so that it can be revolved on its axis.

What I claim is:

1. A pipe wrench, comprising a jaw formed of two curved bands of sheet metal arranged broadside of the axis of the jaw and hinged together, a toothed block secured against the outer side of the free end portion of one band and arranged diametrically opposite to its hinge, a lever provided with teeth for engaging with the toothed block, and a link pivotally connecting the free end portion of the other band with the said lever.

2. A pipe wrench as set forth in claim 1, and having also facing material arranged over the said bands and comprising layers of textile material secured together and provided with plugs of cork.

In testimony whereof I have affixed my signature.

DONALD M. STAINBROOK.
